[57] **CLAIM**

The ornamental design for a decorative pencil holder, as shown and described.

DESCRIPTION

FIG. 1 is a perspective view of a decorative pencil holder showing my new design;

FIG. 2 is a perspective view thereof, shown without the environmental structure;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The dotted line showing of the pencils in FIG. 1 shows environmental structure which does not form a part of the claimed design.
